UNITED STATES PATENT OFFICE.

CHARLES A. STEINUS, OF DETROIT, MICHIGAN.

TABLE.

Application filed April 20, 1921. Serial No. 462,963.

To all whom it may concern:

Be it known that I, CHARLES A. STEINUS, a citizen of the United States, and resident of Detroit, in the county of Wayne and State of Michigan, have invented new and useful Improvements in Tables, of which the following is a description, reference being had to the accompanying drawings, which are a part of this specification.

10 My invention relates to improvements in tables.

It is the object of the invention to provide an improved form of foldable table, which is adaptable for serving meals in rooms of hotels and hospitals, etc., or for use as a card table, and which provides a construction wherein, when the parts are adjusted for use, a most rigid, although exceedingly light and firm, structure is provided; and when folded or collapsed, the collapsing is such that the table takes up but a minimum of space.

The invention furthermore contemplates as a feature the utilization of a space beneath the table top for a removable receptacle for dishes containing food, with provision for heating said receptacle, when the same is removed, and the order is being filled by the waiter or kitchen steward, and after all the food for a certain room has been placed in the receptacle, the latter is inserted in the table, and said table, owing to its lightness, can then be easily carried to the room where the meal is to be served, this being particularly advantageous in hotels and hospitals where meals are so frequently served in the rooms.

A further object is the adaptability, by slight modification, of the table being carried in its collapsed condition, on an automobile trip, for use as a luncheon table, the modification being such that the table can be readily fitted to and carried on the spare tire at the rear of the machine.

With the above main objects, and other incidental objects, in view, the invention consists of the devices and parts and combinations, or the equivalents thereof, as hereininafter more fully described.

In the accompanying drawings, Fig. 1 is 50 a perspective view of the table in position for use;

Fig. 2 is a sectional view of one of the end hinge links for the table top sections, show-

ing the hinge pins therefor and being taken on the line 2—2 of Fig. 1;

Fig. 3 is a an underside view of Fig. 1;

Fig. 4 is a transverse section on the line 4—4 of Fig. 3.

Fig. 5 is a sectional view through one corner of the table, on the line 5—5 of Fig. 1;

Fig. 6 is a view on an enlarged scale, of one of the intermediate hinge connections for the table top sections, the view being a section on the line 6—6 of Fig. 3;

Fig. 6^a is a sectional view, on an enlarged scale, taken on the line 6^a—6^a of Fig. 3.

Fig. 7 is a side elevation on a reduced scale, of the form of table shown on Sheet 1 of the drawings, showing the table in its 70 folded condition.

Fig. 8 is an end view of Fig. 7;

Fig. 9 is a sectional view on the line 9—9 of Fig. 3, on an enlarged scale;

Fig. 10 is a view of a modified form of the 75 table equipped with a receptacle for containing food;

Fig. 11 is a sectional view on the line 11—11 of Fig. 10; and

Fig. 12 is a modification wherein the table 80 is adapted to be carried on, and secured to, the spare tire of an automobile.

The table top consists of two longitudinal sections 11 and 12, which are hinged together at their abutting edges by downwardly opening hinges consisting each of two members. These members are provided with flange plate members 13 and 14, fitted beneath the respective table top sections and having screws 15 passing therethrough and entering said table top sections.

The plate 13 is provided with an upwardly extending flange 16 having at its upper edge, and at opposite ends thereof, inwardly extending ears 17—17 provided with rounded 95 edges. This plate member 13 is also provided with a lower extension 18.

The other plate member 14 is likewise provided with an upwardly extending flange 19, having at its upper edge inwardly projecting 100 ears 20—20, with rounded edges which meet the rounded edges of the ears 17, so as to provide rolling surfaces for the free turning of the two hinge members.

The flange 19, near its lower edge, and at 105 opposite ends, is provided with two inwardly

extending lugs 21-21, which, when the hinge members are in their normal position, fit into the space between the ears 17-17 and rest on the top of the extension 18 of 5 plate 13. A top space is formed between ears 17 and 20, and in this space is fitted a link piece 22. Hinge pins 23-23 pass through eyes in the ears 17 and 20, and also through the corners of the link piece. This link 10 piece, therefore, in conjunction with the hinge pins, forms a means for hingedly connecting the two members of the hinge together.

One pair of hinge members might be 15 sufficient to provide an intermediate hinge joint for the table top sections, but I prefer to provide two of these intermediate hinge sections, spaced a desired distance apart, as shown most clearly in Figs. 1 and 3 of 20 the drawings.

The opposed edges of the table top sections, where these intermediate hinges are located, is cut away so as to receive the upwardly extending flanges 16 and 19 of the 25 respective hinge sections, so that the upper edges of said flanges and the upper surface of the link piece 22 will be flush with the upper surface of the table top sections.

Near the ends of the table top sections, 30 and across the meeting edges thereof, are disposed additional hinge connections, consisting of narrow links 24-24, the opposed edges of the table top sections being cut away to accommodate the upper surfaces of 35 said links, and the said links extending across the meeting edges of the table top sections. The portions of these links 24 beneath the table top are provided with eyes 25-25 which receive hinge pins 26-26, 40 said hinge pins also entering lugs 27-27 on the underside of the table top sections.

The supporting legs of the table consist 45 each of two sections, the lower section 28 being preferably of wood. The upper section 29 is preferably of light metal, and also preferably angular in cross section. The lower end of each angular leg section 29 is bolted or riveted to the upper end of the lower leg section 28.

50 The table top sections are pivotally connected at their corners to the upper sections of the supporting legs by means of pivot pins 30, each pin extending through one of the flanges of the upper leg section and 55 entering an eye in the depressed corner of the table top section, as most clearly shown in Fig. 5.

The top ends of the upper leg sections 60 are flanged inwardly, as indicated by the numeral 29', to form a ledge beneath which the corner of the table top sections extends, and the depressed portions of this corner of the table top section receives the ledge 29', as most clearly shown in Fig. 5. The 65 ledge referred to, therefore, forms a stop

to limit the upward movement of the table top sections on their hinges. When the table top sections are turned downwardly in the operation of collapsing the table, or in other words, when the inner longitudinal edges of said table top sections are forced downwardly, the end transverse edges of the table top sections are received or housed in the angles of the upper angular leg sections 29. When the table is fully collapsed, 70 it is folded in the compact condition shown most clearly in Figs. 7 and 8 of the drawings.

The outer longitudinal edge of each table top section is provided with a metallic border strip 31, of the form of a square tube in cross section.

Side braces are provided of arch-shaped form. Each side brace preferably consists of two members 32-32, which are connected together at their abutting ends preferably by means of a right and left hand threaded screw 33. The abutting ends are formed with screw threaded recesses having respectively opposite threads, and the right hand threads of one half of the screw are turned into the recess having the right hand threads; and the left hand threaded recess of the other member of the brace is made to engage and turn upon the left hand threads of the screw, and is turned thereon until the two ends of the brace meet. The lower ends of the brace members or sections are reduced and firmly connected by rivets or other securing devices to the lower sections 28 of the legs. These brace members are also preferably of a square tubular form in cross section, and are provided near their upper ends interiorly with a solid portion 34, through which a vertical screw 35 is turned, said screw entering a block 36 disposed within the border strip 31. By this means each arch-shaped section of the brace is secured to the border strip 31 adjacent thereto.

A turnable or hinged connection should be provided between the outer longitudinal edges of the table top sections and the arch-shaped braces, as otherwise the table top sections would be prevented from turning 115 downwardly when it is desired to collapse the table. To provide for this, I employ hinged leaves 37-37 connected to the underside of the table and extending, respectively, outwardly and into the sections 120 composing one of the arch-shaped members, where they are pivotally mounted upon pins 38-38, each of said pins having one end supported in the side of the solid portion 34, and its opposite end in a vertical web 125 38'. These pivots or hinges work in conjunction with the corner hinges or pins 30 in permitting the table top sections to be turned downwardly when it is desired to collapse the table.

When the table is unfolded so as to bring the table top sections to a horizontal position, it is, of course, necessary that these top sections should be supported in their horizontal position. To provide for this, I employ at opposite ends of each table top section, two supporting arms, designated, respectively, 39 and 40. The ends of each arm are adapted to swing on vertical pivots 41 extending upwardly from the table leg.

Each table top section, at opposite ends, is provided, on its underside, with short angle pieces 42-42. When the arm 39, for instance, is swung to the supporting position shown in Fig. 4, it seats itself in the back portion of the angle pieces 42. The other supporting arm 40 is then swung to supporting position, and overlaps the arm 39 and seats itself in the forward portions of the angle pieces 42 (see particularly Fig. 4 of the drawings). When it is desired to collapse the table, arm 40 is first swung to a position so as to extend longitudinally of one of the table top sections, and then arm 39 is free to be swung to a position to extend longitudinally of the other table top section.

Figs. 10 and 11 illustrate a modification of the invention wherein is disposed beneath the end of the table top sections, a receptacle subdivided into a series of compartments for containing hot dishes. In this modification the supporting arms 39 and 40, at one end, are omitted to afford space for the introduction of the food container receptacle. This food container receptacle is indicated by the numeral 43, and is divided into compartments by means of horizontal partitions 44, and is held securely in place by means of eccentrics 44'-44'. The receptacle and these eccentrics, therefore, serve the function of supporting the table top sections at this end of the table. The box is provided with hinged doors 45-45 to provide ready access to the interior. The upper end of the box lies beneath the short angle piece 42 and is provided with angular plates 46 which are adapted to removably fit a keeper 46' secured to the under side of the table top.

The lower edge of the food receptacle rests upon two arms 47-47 having their inner ends hinged together by means of a hinged link 48, similar in construction to the hinged links connecting the inner edges of the table top sections near the outer ends of said sections, and illustrated in detail in Fig. 2 of the drawings. The opposite ends of the arms 47 are pivotally connected by pins 49-49 to the upper angular leg sections. In this modification it is necessary that the upper leg sections be made considerably longer than the lower leg sections so as to accommodate therebetween the food receptacle.

In using this modified form of construction, the receptacle is removed from the table, and the compartments are filled with dishes containing hot food, in the kitchen, and for the purpose of keeping the dishes containing the food hot while in the receptacle, and before the order is completely filled, I provide a socket 49', which may be connected up to a source of electrical supply. After the order is filled, the receptacle is reinserted in place beneath the table, and said table then carried to the room where the food is to be taken, and by opening the doors 45, the dishes may be removed from the compartments and placed upon the table top, ready to be served.

When it is desired to collapse this form of the device, it is necessary to entirely disconnect and remove the food receptacle. After the removal of the receptacle, the table can be collapsed as in the principal form of construction, the arms 47-47 being turned upwardly on their central connecting hinge.

The modification illustrated in Fig. 12 shows the construction of table which is adapted to be supported on, and secured to, the spare tire of an automobile, so that the table can be conveniently carried on an automobile trip, and used for serving food thereon. In this figure of the drawing, the numeral 50 indicates the automobile, and 51 the spare tire at the rear thereof. In view of the fact that the side braces of the table are arched or of curved form, they will fit over the spare tire, and conform to the contour thereof, as clearly shown in Fig. 12. It would not do, however, in a table adapted to be thus carried, for the table top sections, when the table is in collapsed position, to turn downwardly on the hinged connections, as this would interfere with the fitting of the arched braces to the automobile tire. In view of this, the construction is modified to the extent of reversing the hinges which connect the inner edges of the table top sections together, the reversal permitting of the turning upwardly of the table top sections, as clearly shown in Fig. 12.

When the table is thus supported by the tire, in order to securely hold the table to the tire, straps 52 are employed, the top strap 52 passing over the upper edges of the table top sections and thence downwardly and beneath the tire, and the shorter side straps passing around the legs of the table and around the tire. It is also preferred that the table and the rear tire be covered with a suitable fabric covering or bag, and a fragment of this is illustrated in Fig. 12, and indicated by the numeral 53.

From the foregoing description of my invention, it will be seen that it covers a form of collapsible table which is not only light in weight, but which, furthermore, is strong and when opened in position for use, is rigid

and firmly braced throughout. The peculiar construction employed also provides for the collapsing of the table with a minimum of trouble, the table when collapsed being in a flat condition, and taking up but very little room.

What I claim as my invention is:

1. In a foldable table, the combination of a top consisting of sections, having their inner edges adjacent and parallel, supporting legs, the upper portions of which at least being angular in cross section, hinges connecting the inner edges of the top sections, other hinge connections between the legs and the corners of the table top sections, whereby said sections are permitted to be folded together, and their opposite end edges, when the table top sections are folded together, being brought into the channels of the angular portions of the supporting legs, and means for supporting the table top sections in their horizontal position.
2. In a foldable table, the combination of a table consisting of sections, having their inner edges adjacent and parallel, and having their corners depressed, supporting legs, the upper portions of which at least being angular in cross section, and the upper ends of said legs provided each with an inwardly projecting ledge beneath which the depressed corner of the table top section fits, hinges connecting the inner edges of the table top sections, other hinge connections between the legs and the corners of the table top sections, whereby said sections are permitted to be folded together, and their opposite end edges brought into the channels of the angular portions of the supporting legs, and means for supporting the table top sections in their horizontal position.
3. In a foldable table, the combination of a top consisting of sections, having their inner edges adjacent and parallel, supporting legs, hinges connecting the inner edges of the table top sections, other hinge connections between the legs and the corners of the table top sections, whereby said sections are permitted to be folded together and the legs brought adjacent to the folded top sections, a supporting arm pivoted to the legs and adapted to be turned under and across the table top sections to support said sections in their horizontal position, and to be turned in the opposite direction to permit of the table top sections being folded together.
4. In a foldable table, the combination of a top consisting of sections, having their inner edges adjacent and parallel, supporting legs, hinges connecting the inner edges of the table top sections, other hinge connections between the legs and the corners of the table top sections, whereby the said sections are permitted to be folded together and the legs to be brought adjacent to the folded table top sections, angle pieces se-

cured to the undersides of the respective table top sections, near the ends thereof, and supporting arms pivoted to the legs and adapted to be turned under and across the table top sections and into engagement with the angle pieces, one arm overlapping the other in said angle pieces.

5. In a foldable table, the combination of a top consisting of sections, having their inner edges adjacent and parallel, supporting legs, hinges connecting the inner edges of the table top sections, other hinge connections between the legs and the corners of the table top sections, whereby said sections are permitted to be folded together and the legs brought adjacent to the folded top sections, a supporting arm pivoted to the legs and adapted to be turned under and across the table top sections to support said sections in horizontal position, and to be turned in the opposite direction to permit of the table top sections being folded together, and side braces connected to the legs and extending upwardly and having hinged or pivoted connections with the outer edges of the respective table top sections.

6. In a foldable table, the combination of a top consisting of sections having their inner edges adjacent and parallel, supporting legs, hinges connecting the inner edges of the table top sections, other hinge connections between the legs and the corners of the table top sections, whereby said sections are permitted to be folded together and the legs brought adjacent to the folded top sections, a supporting arm pivoted to the legs and adapted to be turned under and across the table top sections to support said sections in horizontal position, and to be turned in the opposite direction to permit of the table top sections being folded together, and arch shaped side braces, each having its lower ends connected to the supporting legs, and having its upper central portion hingedly or pivotally connected to the outer edge of the table top sections.

7. In a foldable table, the combination of a top consisting of sections having their edges adjacent and parallel, supporting legs, hinges connecting the inner edges of the table top sections, other hinge connections between the legs and the corners of the table top sections, border strips for the opposite side edges of the table top sections, each border strip being of square tubular form in cross section, an arch shaped brace for each table top section, the said brace being angular in cross section, and the lower ends thereof rigidly secured to two of the supporting legs, and the upper central portion of each brace being located beneath one of the border strips and being secured thereto by means of screws passing through solid portions formed in the arch shaped brace, and passing into the blocks within the tubu- 130

lar border strip, hinge connections between the table top sections and the arch shaped brace pieces, and means for supporting the table top sections in their horizontal position.

8. In a foldable table, the combination of a table consisting of sections, having their edges adjacent and parallel, supporting legs, hinges connecting the inner edges of the table top sections, other hinge connections between the legs and the corners of the table top sections, border strips for the opposite side edges of the table top sections, each border strip being of square tubular form in cross section, an arch shaped brace for each table top section, the said brace being angular in cross section, and the lower ends thereof rigidly secured to two of the supporting legs, and the upper central portion of each brace being located beneath one of the border strips, and being secured thereto by means of screws passing through solid portions formed in the arch shaped brace, and passing into the blocks within the tubular border strips, a hinge connection consisting of a leaf secured to the underside of the table top section and extending outwardly into the arch shaped brace and freely mounted at its outer end on a pin carried in bearings in the arch shaped brace, and means for supporting the table top sections in their horizontal position.
9. In a foldable table, the combination of a top consisting of sections having their edges adjacent and parallel, supporting legs, hinges connecting the inner edges of the table top sections, other hinge connections between the legs and the corners of the table top sections, border strips for the opposite side edges of the table top sections, each border strip being of square tubular form in cross section, an arch shaped brace for each table section, angular in cross section, the lower ends thereof rigidly secured to two of the supporting legs, and the upper ends thereof being connected together by a screw turning into threaded recesses in the ends of the said sections, and the upper central portion of the sectional brace being located beneath one of the border strips and being secured thereto by means of screws passing through solid portions formed in the arch shaped brace, and also passing into the blocks within the tubular border strip, hinge connections between the table top sections and the arch shaped brace piece, and means for sup-

porting the table top sections in their horizontal position.

10. A foldable table, comprising a top consisting of sections having their inner edges adjacent and parallel, a hinge connection for the inner edges of the table top sections, said hinge connection consisting of two plates secured to the undersides of the respective table top sections, and said plates provided with upwardly extending flanges having inwardly extending contacting lugs with rounded ends, and one of said plates also provided with an extension, and the other with a projection adapted to overlie said extension when the hinge members are brought together, a hinge link within the space of the upwardly extending flanges and the end lugs of said flanges, and pivot pins extending through the said end lugs and through the hinge link, the contiguous edges of the table top sections being cut away to accommodate the upper flanges of the hinge members, and the upper surfaces of said flanges and the upper surface of the link being flush with the upper side of the table top sections, supporting legs, hinge connections between the supporting legs and the corners of the table top sections, whereby said sections are permitted to be folded together and the legs brought adjacent to the folded sections, and means for supporting the table top sections in their horizontal position.

11. In a foldable table, the combination with a top consisting of sections having their inner edges adjacent and parallel, of a hinge connection for the inner edges of the table top sections, said hinge connection consisting of two plates secured to the undersides of the respective table top sections, and said plates provided with upwardly extending complementary lugs with rounded edges, and a hinge link within the space of the upwardly extending flanges and the end lugs of said flanges, said link having pivot pins extending therethrough and through the end lugs, the contiguous edges of the table top sections being cut away to accommodate the upwardly extending flanges of the hinge members, with the upper surfaces of said flanges and the upper surface of the hinge link flush with the upper side of the table top sections.

In testimony whereof, I affix my signature.

CHARLES A. STEINUS.
